AUTOMATIC LAUNDERING MACHINE AND
PUMP DRIVE THEREFORPeter Eduard Geldhof, St. Joseph, Mich., assignor
to Whirlpool Corporation, a corporation of New
York

Application April 30, 1948, Serial No. 24,184

2 Claims. (Cl. 68—23)

1

My invention relates to automatic clothes washing, rinsing and drying machines and more particularly to an improved pump structure for use therewith.

In one form of automatic laundering machine, mechanism is provided whereby the user may insert clothes or other objects to be laundered, set the controls of the machine to initiate the laundering cycle, and return at a later time to find the clothes or other objects completely cleansed and rinsed and the preliminary drying or water extracting operation performed. Such mechanism is of particular utility for home use as it relieves the burden of laundering or cleaning processes and obviates the necessity of constant attention on the part of the user.

In order to provide maximum efficiency in the utilization of warm soapy water, mechanism is provided to pump the wash water from the tub in which laundering operations take place to a suitable receptacle such as, for example, an ordinary wash tub. For subsequent washing operations, this water is pumped back into the tub and re-used. Mechanisms for achieving this operation have heretofore included separate drive motors operative to achieve this pumping operation. While this has successfully permitted the desired operation, it results in a substantial increase in cost of the machine and, in addition, introduces an additional electrical motor which is subject to the maintenance difficulties inherently associated with such devices.

Certain features of the structure disclosed in the present application are described and claimed in the joint patent applications of Peter E. Geldhof and Luther Ringer entitled "Laundering Machine," Serial No. 787,060, now Patent No. 2,610,498, and "Automatic Washing, Rinsing and Drying Machine," Serial No. 491,618, now Patent No. 2,521,159 dated September 5, 1950, both assigned to the same assignee as the present invention.

It is accordingly a general object of the present invention to provide an improved automatic laundering machine.

A more specific object of the present invention is to provide an improved mechanism for pumping liquid from a storage container to the washing receptacle of an automatic washing machine.

A further object of the present invention is to provide an improved pump mechanism for pumping liquid from a storage container to the washing chamber of an automatic washing machine and which does not require an additional electric motor.

2

Yet another object of the present invention is to provide an improved self-priming pump construction suitable for use in a washing machine or the like.

5 A further object of the present invention is to provide an improved drive mechanism for the pump of an automatic laundering machine and which has features of construction, combination and arrangement whereby a simple and effective structure is provided which may be readily manufactured and which is capable of effectively driving the pump in response to the actuation of an electrical control mechanism.

The novel features which I believe to be characteristic of my invention are set forth with particularity in the appended claims. My invention itself, however, both as to its organization and method of operation, will best be understood by reference to the following description taken in conjunction with the accompanying drawings.

15 Figure 1 is an isometric front view of a complete automatic laundering machine constructed in accordance with the principles of the present invention;

20 Figure 2 is a rear elevational view of the machine of Figure 1 with the shroud and portions of the rear cover removed to expose portions of the control elements to view;

25 Figure 3 is a side elevational view of the mechanism of Figure 1, with portions broken away to show the various components of the mechanism, and the spindle and associated parts in cross section to show the construction of the agitator and basket and the drive mechanism therefor;

30 Figure 4 is a cross-sectional view through the axis IV—IV, Figure 2, showing the drive mechanism of the machine;

35 Figure 5 is a diagram illustrating the cycle of operation of the machine of the present invention;

40 Figure 6 is an electrical circuit diagram of the machine of the present invention;

45 Figure 7 is an enlarged fragmentary view of the pump drive mechanism as shown in Figure 4, but with the idler pulley in an engaged position;

50 Figure 8 is a fragmentary cross-sectional view through the axis IX—IX, Figure 4, showing the internal construction of the pump mechanism of the present invention;

55 Figure 9 is an exploded view like Figure 8, but showing the positioning of the parts of the pump prior to assembly;

60 Figure 10 is a cross-sectional view through axis X—X, Figure 8;

Figure 11 is a cross-sectional view through the axis XI—XI, Figure 8;

Figure 12 is a view of the gear box of the machine of Figure 1; and

Figures 13 and 14 are fragmentary cross-sectional views through axis XIII—XIII, Figure 7, and axis XIV—XIV, Figure 7, respectively, and with parts in elevation.

The laundering machine shown in the drawings comprises a tub T which defines a clothes laundering chamber and is supported by the support structure S. The support structure S is covered in its rear portion by a shroud 20 which extends upwardly behind the tub T to enclose the operating structures extending up to the top of the unit. The outer covering of the support S snugly fits the tub T to form a sanitary and attractive shape as will be evident from the figure. The shroud and the portions of the tub and the support structure exposed to view are given a coating of vitreous enamel or similar material to present an attractive and readily washed surface.

The tub T contains a cylindrical inner rotatably mounted clothes container or basket 22 (Figure 3) together with an agitator 24 mounted concentrically therewith for oscillating motions during clothes washing and rinsing. An upper housing structure 26 is attached to the upper periphery of the cylindrical outer tub structure 28 (Figure 3) and is of generally annular shape with an inner downwardly extending throat portion 30 to guide clothes or other objects into the basket 22. A circular cover or cap 32 fits on the upper portion of the structure 26 and is provided with a handle 33 to facilitate removal thereof to place clothes in the machine or to remove the same therefrom.

The support structure S (Figure 1) sustains the tub portion T in position, and, in addition, contains, the mechanical drive elements for the basket 22 and the agitator 24 contained therein. Moreover, pumps and other mechanisms required to achieve the fluid flow incident to the operation of the machine are mounted within the support structure S. This structure further includes a horizontal plate 34 (Figure 3) which not only forms a support directly underneath the tub portion T but also extends backwardly for forming a mounting plate upon which the cycle control switch 36 (Figure 2), the temperature control switch 38 (Figure 2), and the fluid temperature control valve 98 (Figure 2) are mounted.

The shroud 20 (Figure 1) consists of a stamped metal sheet encompassing the portions of the support structure S located underneath the tub T and, in addition, extends both backwardly and upwardly to cover the rear portions of the support structure S. Moreover, the shroud 20 forms a horizontal top surface 40 (Figure 1) in horizontal alignment with the cover 32 of the tub portion T. Operating handles 42 and 44 for the temperature control switch 38 and the cycle control switch 36, respectively, extend through this top surface of shroud 20 to provide a convenient readily adjustable means for controlling the operation of the laundering machine.

Operation

The features of the present invention can best be understood by a preliminary discussion of the operating cycle thereof taken in connection with Figures 5 and 6. Figure 5 is a diagram indicating the condition of the cam actuated switches

controlling the energization of the various elements identified thereon at the various times in the operating cycle, these times being identified by the indication in the "minutes" line of the diagram. It will be understood, of course, that an element may be indicated as energized in the diagram of Figure 5, when in fact some other portion of the energizing circuit is open and for that reason the element does not operate.

The cycle control switch, shown diagrammatically in Figure 6, for example, comprises a plurality of cams 122, 106, 64, etc., with the associated switches 126, 114, 68, etc., in cooperative engagement therewith for opening and closing movements as the cams are rotated. The cams are mounted on a common insulated shaft 50 which is driven by the timer motor 108 which, for the particular embodiment of the present invention herein described, is a synchronous alternating current motor capable of rotating the shaft 50 one revolution in approximately 45 minutes. The cams 122, 106, 64, etc. are aligned relative to the shaft 50 to provide the desired sequence of control and the knob 44 is provided with suitable markings to indicate the point on the operating cycle to which the shaft 50 is aligned or set.

In the view of Figure 6, the shaft 50 and the associated cams are rotated by motor 108 in the direction indicated by the arrows 50a, and the shaft is shown as rotated to the position corresponding to the beginning of the period identified at A (Figure 5), this period being the preliminary period during which the used suds are returned to the tub T to provide wash water for a subsequent cycle of operation.

Assuming that the laundering machine is to be started from an unenergized condition and that the storage reservoir provided to retain used suds is empty, the knob 44 is rotated to the position corresponding to the beginning of the fill period and is then depressed to close the single pole switch indicated generally at 46. This switch may, for example, comprise a conducting disk 48 attached to the insulated shaft 50 of the switch 46 for cooperative engagement with the two contacts 52. These contacts are mounted in a common plane perpendicular to the axis of shaft 50 and are located relative to the length of this shaft at a point such that when the shaft is depressed the contacts engage the disk 48, thereby defining closed circuits for the passage of electrical current.

When the knob 44 is rotated to the condition corresponding to the beginning of the "fill" period, the switch 66 rides in the notch 62a of the cam 62 and the switch 68 rides in the notch 64a of the cam 64. Switch 68 thereupon drops down to connect conductor 70 to conductor 72, and the switch 66 drops down to connect conductor 70 to conductor 74. Conductors 72 and 74 are connected to switches 76 and 78 which in turn are connected to the mix water solenoid 80 and the hot water solenoid 82, respectively. These solenoids are connected on their opposite ends to the conductor 84 which is in electrical connection with the prong 56b of plug 56.

The conductor 70 is connected to the conductor 60 through the float switch 86 which is in the position shown in Figure 6 when the liquid level in tub T is below a predetermined level, thereby connecting conductors 88 and 70. Thus when the unit is energized by depressing the knob 44, the solenoids 80 and 82 are connected to the source of electrical energy through the switches 76 and 78,

respectively, the former being connected to circuit through the switch 68 and the latter through the switch 66.

The switches 76 and 78 are actuated by cams 92 and 94, respectively, and which are mounted on the insulated shaft 96 of the temperature control switch 38 to which knob 42 is connected. This knob may be rotated to any one of three positions, a first position corresponding to closure of both switches 76 and 78 (the position indicated in Figure 6), a second position corresponding to closure of switch 76, and a third position corresponding to closing of switch 78. This action is achieved by providing notches 94a and 94b in the cam plate 94 and notches 92a and 92b in the cam plate 92, the notches 94b and 92a being aligned relative to the shaft 96 so that when the knob 42 is in the position indicated diagrammatically in Figure 6, switches 78 and 76 ride in these notches and are closed to energize both solenoid 80 and solenoid 82. When the knob 42 is rotated to align notch 94a with the switch 78, only solenoid 82 is energized, and when knob 42 is rotated to align notch 92b with the switch 76, only solenoid 80 is energized.

The physical structure of the solenoids 80 and 82 is shown in the rear elevational view of Figure 2. As is evident from this figure, they are mounted above the temperature control valve 98. This valve includes hose couplings 98a and 98b to receive hose connections to sources of hot and cold water, respectively, and is connected to a hose 100 which supplies water to the tub T through the hook-shaped tube 102. When electric current is caused to flow through "mix" solenoid 80, for example, a movable plunger is raised by the magnetic forces associated with the current flow and a fluid operated valve in the unit 98 connects the couplings 98a and 98b to the hose 100 through a fluid mixing chamber, and the relative quantities of fluid flowing from these couplings to the hose 100 are regulated by temperature sensitive elements in the valve 98 to a relatively low temperature to cause relatively cool water to flow into the tub T. On the other hand, when the "hot" solenoid 82 is energized with electric current, the coupling 98a, which is attached to a source of hot water (not shown), is connected to the hose 100 to cause hot water to flow into tub T. When both solenoids are energized, water of intermediate temperature passes into the tub T.

From the foregoing it will be seen that when the knob 44 is depressed to energize the mechanism at the start of the laundering cycle, liquid of temperature regulated in accordance with the setting of the temperature control switch 38 flows into the tub T. When the required amount of water passes into the tub, the level control switch 86 disconnects conductors 88 and 70 (Figure 6) and thereby causes this fluid flow to discontinue.

When the fluid level in the tub T rises to the point where level control switch 86 disconnects the conductors 88 and 70, the conductors 88 and 90 are connected with the result that motor 54 is energized through the circuit which can be traced from the prong 56a of plug 56 to conductor 58, switch 46, conductors 60 and 88, level control switch 86, conductors 90 and 104 through motor 54, and finally back to prong 56b through conductor 84. Moreover, the cam switch 110 in the "fill" and "wash" condition (Figure 5) is in the closed position because notch 112b of cam 112 bears thereagainst during this period. This completes the electrical circuit from conductor

104 (which is energized through the level control switch 86), switch 110, agitator solenoid 109, and conductor 84. As will be described in further detail hereafter, current flow through solenoid 109 causes engagement of mechanical elements which drive the agitator 24 (Figure 3) from the motor 54 to cause the former to execute oscillatory or reciprocating clothes washing movements. Thus, upon completion of the filling of the tub T, the agitator is energized to wash clothes contained in the basket 22.

When the fluid in the tub T actuates the fluid control switch 86, the timing motor 108 is energized through the circuit comprising this switch, conductors 90 and 104, motor 108, conductor 111, and conductor 84 to prong 56b of plug 56 and from prong 56a of plug 56 to conductor 58, and switch 46 to conductor 88 and switch 86. Hence, motor 108 drives the shaft 50 in the direction indicated to cause the operating cycle to progress.

During the first ten-minute period identified as "fill" (Figure 5), the above-described conditions prevail and the agitator operates when the tub T is full. Upon completion of this period, the switches 66 and 68 ride out of the notches 62a and 64a in cams 62 and 64, respectively, and open to disconnect conductors 72 and 74 from conductor 70. In addition, the switch 114 rides in the notch 106a of cam 106 to connect conductor 60 to conductor 104 to render the operation of motor 54 and timer motor 108 independent of the operation of level control switch 86 and the quantity of water in the tub T.

Upon completion of the "wash" period which may, for example, extend for a ten-minute period after the "fill" period, a "drain" period of, for example, six minutes, follows. At this time the switch 110 rides out of notch 112b of the cam 112 and opens to deenergize the agitator solenoid 109. As will be described in further detail hereafter, this causes the agitator 24 to be mechanically disconnected from motor 54 to discontinue the oscillating movements thereof and at the same time mechanically engages motor 54 and the auxiliary pump 128 (Figure 4) to cause the latter to rotate in direction to pump fluid out of the tub T.

Since the operation of the agitator 24 is independent of the level of the fluid in the tub T during the last ten minutes of the "wash" period, the laundering machine may be operated with a reduced quantity of water by manually turning the knob 44 to a position in the "fill" period and depressing the knob to cause the valve solenoids 80 and 82 to be energized in accord with the water temperature desired to cause water to flow into the tub T. When the desired quantity of water is in the tub, the knob 44 may be manually rotated to a position beyond the "fill" period but still in the "wash" period to deenergize the valve solenoids 80 and 82 and cause the agitator to operate despite the fact that the level control switch 86 is not lifted. In this manner small quantities of clothes may be washed without requiring the time or water necessary for a full quantity of clothes.

During the "suds drain" period the switch 118 rides in the notch 120a of cam 120 and closes to actuate the two-way valve solenoid 116. As will be described in further detail hereafter, the resulting current flow in solenoid 116 causes the two-way valve to connect the tub T with the storage reservoir provided to hold the used washing suds. Consequently, the rotations of pump

128 cause water to be pumped out of tub T and into the storage reservoir.

During the last portion of the "suds extract" period, the extractor solenoid 130 is energized by the circuit through conductor 132 and switch 126, the latter being rendered conducting when it rides on the notch 122b of cam 122. Energization of the extractor solenoid 130 causes the basket 22 to be mechanically connected to the motor 54 through a slip clutch assembly which limits the torque exerted by the motor on associated parts of the drive mechanism.

During a short interval of the "suds extract" period, as, for example, the minutes twenty-four and twenty-five (Figure 5), the cam 134 is positioned to align the notch 134a with the switch 136 and thus permit that switch to descend and make contact when the face of the auxiliary cam 134c rides against switch 136. The latter cam is driven by suitable driving elements (not shown) to rotate one revolution per minute, and hence to execute two revolutions in the two-minute period, the notch 134a is aligned with the switch 136. The flat face of cam 134c is shaped to permit switch 136 to close during only a short period as, for example, seven seconds of this time, thus causing the clothes to be sprayed only a relatively short period of time. The spray water is warm fresh water obtained from the temperature control valve 98 when only the solenoid 80 is energized and washes the wash water off the clothes or other objects contained in the tub T.

Toward the end of the extract suds period, at a time which may, for example, be at the conclusion of the twenty-six minute interval (Figure 5) the cam 106 has rotated beyond notch 106a and opens switch 114, thereby disconnecting motor 54 from the source of energizing power since the level control switch 86 is in the down position shown in Figure 6. At this time, the cam 134 has rotated to align cam 134b with switch 136 and energizes the "mix" solenoid 80 through the circuit which can be traced through conductor 138, conductor 70, level control switch 86, conductor 88, conductor 60, switch 46, and conductor 58 to prong 56a of plug 56. During this time, fresh warm rinse water flows into the tub T, and all other operations, including rotation of shaft 60 by timer motor 108, are discontinued.

When the tub T fills, the lever control switch 86 shifts to connect conductors 88 and 90 to energize timer motor 108 and motor 54 through conductor 104. Shaft 50 then rotates and the agitator solenoid 109 becomes energized by reason of the alignment of the notch 112a of cam 112 with the switch 110. This causes the agitator 24 (Figure 3) to execute oscillating motions to rinse thoroughly the clothes contained in the basket 22.

After about two minutes' agitation, which may, for example, terminate at minute 28 (Figure 5), the "drain rinse water" period commences. At this time the switch 110 no longer rides in the notch 112a of cam 112 and opens to deenergize the agitator solenoid 109 to cause the agitator to be mechanically disconnected from motor 54 and discontinue the oscillating motions thereof. De-energization of agitator solenoid 109 further causes the motor 54 to be mechanically engaged with pump 128 (Figure 4) as is described in further detail hereafter, and causes this pump to rotate in direction to withdraw water from tub T. Since the two-way valve solenoid 116 is not energized during this period, the interior of the tub T is in fluid communication with the drain pipe

(not shown) through the pump 128, and the two-way valve and rotation of the pump 128 cause the water to be pumped from the tub T to the drain pipe.

Approximately two minutes after the foregoing draining operation commences as, for example, at minute 31 (Figure 5), the "extract rinse water" period is started. At this time the switch 126 rides into the notch 122a in cam 122 and thereby connects conductor 70 to the extractor solenoid 130. This causes the motor 54 to engage the basket 22 through a slip clutch which operates to limit the torque exerted on the drive mechanism. The basket 22 is thereupon accelerated to a high rotational velocity as rapidly as the slipping ability of the clutch permits, and water is driven out of the clothes therein by the centrifugal forces associated with the rotational motion.

If it should happen that the pump 128 does not quite remove all the water from the tub T during the two minutes allotted for this action, overload of the drive mechanism is prevented by the slipping clutch interposed between the motor 54 and the basket 22. Moreover, the pump 128 continues in operation, and when the water is removed the drive mechanism is then capable of accelerating the basket 22. During the "drain rinse water" and "extract rinse water" periods the pump 128 continues to rotate to remove any water in the tub T.

At the beginning of the "extract rinse water" period as, for example, minute 31, the notch 134d rides against the switch 136 to energize solenoid 80 when the flat face of the cam 134c rides against that switch. This causes a spray of about 7 seconds' duration during the one-minute period when the notch 134d is aligned with the switch 136.

Upon completion of the "extract rinse water" period, the entire unit is shut off when cam 106 rotates to the point wherein switch 114 rides out of notch 106b and is opened. The cover 34 of the tub T may then be removed and the laundered clothes taken out of the unit.

When it is next desired to operate the machine, the cycle control switch 36 may be placed in the position corresponding to the region identified as A (Figure 5) which is the "suds return" condition. At this time, the suds pump solenoid 124 is energized through the conductor 112, the cam switch 126, and the conductor 88, switch 126 connecting conductors 70 and 112 in this period by reason of the fact that it rides on the nib 122c of cam 122. The two-way valve solenoid 116 is energized at this time through the switch 118 which rides in the notch 120b of cam 120, thus shifting the two-way valve to connect the storage reservoir with the tub T and thereby enabling the suds pump to draw water from the storage reservoir to the tub T and fill the latter.

During the foregoing operation, the main drive motor 54 is energized through the circuit that may be traced from the conductor 58 through the switch 46 to conductor 60. From that conductor, the circuit may be traced through the switch 114 to the conductor 104, the switch 114 being closed since it rides in the notch 106c of the cam 106.

The foregoing conditions prevail so long as the switch 126 rides on the nib 122c of cam 122 and switch 114 rides in the notch 106c of cam 106, a time period that may, for example, continue for three minutes. If this time period expires before the tub T is filled, the "fill" period (Figure 5) begins when the cycle previously discussed commences, the first step in the operation being the

addition of fresh water through the temperature control valve 98 (Figure 2) to cause the level of the water in the washer to rise to the level fixed by the level control switch 86.

During the period A (Figure 5) the agitator solenoid 109 is energized through the switch 110 which is in the closed position during this time because it rides in the notch 112b of cam 112.

Structure

The main drive motor 54 is mounted on a bracket 54b attached to the rear portion of the vertical support member 150, as seen in cross section in the upper right-hand portion of the view of Figure 4. The motor, together with the support member 150, may also be seen in the rear view of Figure 2 and, as will be further evident from this view, is mounted in a pair of elongated slots 150a by support bolts 54d. As will be evident from Figure 4, a pulley 54c is attached to the motor 54 and engages the belt 152 which encircles the actuator drive pulley 154, the pump drive pulley 156 and the extractor drive pulley 158. Moreover, the belt 152 extends to a position adjacent the suds pump drive pulley 300.

The construction and operation of the agitator drive mechanism is described in detail in the pending application of Peter Eduard Geldhof and Luther Ringer, Serial No. 787,060, entitled "Laundering Machine" and assigned to the same assignee as the present invention. As indicated in Figures 4 and 12, the pulley 154 driven from the belt 152 is mounted coaxially with a pinion 154a, and is keyed or otherwise secured to said pinion for rotating the same. The pinion 154a meshes with and drives a gear 162. The latter drives the crank arm 164 to cause the sector gear 166 to execute reciprocating movements which are imparted to the agitator drive gear 172 to cause the agitator 24 to execute clothes washing reciprocating movements.

Rectilinear movements of the arm 176 which are controlled by energization of the solenoid 109 serve to connect the gear 172 to the agitator 24 as in the aforementioned application Serial No. 787,060. The solenoid 109 is mounted upon an oscillating carriage 170 (Figure 4) which is mounted on the upper end of an oscillating shaft 171, and is oscillatably driven thereby. When this solenoid is energized, the gear 172 is positioned to energize the agitator 24, but when the solenoid is deenergized, the agitator 24 rides free of the drive mechanism as in application Serial No. 787,060.

Energization of the solenoid 130 selectively drives the basket 22 for clothes drying operations. This is due to the fact that the arm 190 controls the position of the yoke 200 (Figures 3 and 4) to engage or disengage the clutch defined by the bell-shaped member 194 (Figure 3) which is mounted for rotation with the basket 22 and which is axially shiftable to engage the upper surface of the drive pulley 158.

The method by which energization of solenoids 109 and 130 controls the positions of the arms 176 and 190, as well as the details of the construction of the yoke 200 and the clutch 194, are described in further detail in the patent application of Peter Eduard Geldhof and Luther Ringer, Serial No. 787,060, mentioned above.

In addition to controlling the driving engagement between the sector gear 166 and the shaft 174, the operating arm 176 engages or disengages the pump 128. This operation is achieved through the crank 182 and the links 183 and 183a, Figure

4, which couple this arm to the rocker arm 184 which rotatably supports idler pulley 186 on its remote end. When the arm 176 is in the position shown in Figure 4, the rocker arm 184 is rotated to swing idler pulley 186 to a retracted position where it does not engage the belt 152 and permits that belt to pass over pulley 156 without engaging said pulley. Thus pump 128 is not rotated. However, when the arm 176 is shifted toward

10 crank 182 by the action of the control unit 170, the rocker arm 184 is rotated to cause the pulley 186 to bear against the belt 152 and cause that belt to drive pulley 156 and pump 128.

The arm 190 is shifted forwardly or backwardly 15 in accord with the energization of the solenoid 130 on the opposite end of the oscillating carriage 170 from the arm 109, this arm assuming the forward position when solenoid 130 is energized and moving oppositely from the arm 176.

The pump 128 (Figures 3 and 4) is connected 20 by the hose 210 to sump 212 which is in fluid communication with the interior of the tub T. The opposite side of this pump is connected by hose 214 to suds pump 224 which is described in further detail hereafter. This pump is connected 25 on its opposite side to the two-way valve 218 by the pipe 217.

The two-way valve 218 is provided with hose 30

couplings 218a and 218b, one of which is connected to a storage container such as a laundry tub, and the other of which is connected to a drain. The valve 218 is constructed to connect the pipe 217 with the drain when solenoid 116 is deenergized but shifts the rocker arm 222 through linkage 220 when this solenoid is energized. This connects the pipe 217 to the storage container.

The construction of the suds pump 224 and the drive mechanism for use therewith may best be understood by reference to Figures 3, 4, 8, 9, 10 and 11. From the cross-sectional view of Figure 8, it will be evident that the pulley 300 is mounted

30 on the lengthy shaft 302 which has an impeller 304 press-fitted on its remote end. The shaft 302 is supported in the housing 306 by the spaced bearings 308 which are received in the upstanding sleeve portion 310. These bearings are of the bronze composition type. A resilient rubber sleeve 312 bottoms against the inner sleeve portion 314 of the impeller 304 and the graphite block 316 to hold the pulley 300 against the upper sleeve bearings 308 and sustain the complete unit in axial position relative to the sleeve 310. It will be observed that a very effective water seal is provided by the rubber sleeve 312 and the graphite block 316. The fact that the sleeve 312 is under endwise compression which causes the sleeve to bulge slightly outwardly in the middle, results in resiliently urging the block 316 against the end of bearing sleeve 308. Water is thus prevented from creeping up the shaft 302.

35 The housing 306 is of die-cast construction and has a peripheral flange 306a with threaded openings to receive the screws 318. These screws sustain the bowl 320 which is of drawn metal construction and which has a marginal portion 320a (Figure 9) with openings in registry with the threaded openings in the flange 306a to receive the screws 318. A gasket 322 is sandwiched between the flange 320a and the flange 306a to provide a fluid-tight seal.

40 A baffle plate 324 is held against the annular shoulder 306b of the housing 306 by the gasket 322. This baffle plate cooperates with the cavity 334 of the housing 306 to define the chamber in which impeller 304 is located. The baffle plate

further has an opening 324a in registry with the cavity 335 of the housing 306. The intake pipe 326 extends downwardly from the baffle 324 and is held thereon by the lip 328 and the enlarged ridge portion 330. This pipe is enclosed by the bowl 320.

The bolt 332 rides in the block 333 and acts as a drain cock to permit drainage of the bowl 320. The housing 306 defines two pipe portions 350 and 352, the former receiving the hose 214 (Figure 4) and the latter receiving the pipe 217. The cavity 335 (Figure 8) defines a fluid passage from bowl 320 to pipe portion 352. Cavity 334 is in direct communication with the interior of the pipe portion 350.

From the foregoing description, it will be evident that when the impeller 304 is rotated, the fluid within the chamber 334 is also rotated and develops centrifugal forces which draw the fluid up the pipe 326 and into the hose 214 which leads to pump 128 and which is in fluid communication with the interior of the tub T by hose 210 and the sump 212. Thus rotation of this impeller causes fluid to pass from the two-way valve 218 to the tub T.

It is the purpose of the idler wheel 336 (Figure 7) to provide selective engagements between belt 152 and the pulley 300 in accord with the energization of the suds pump control solenoid 124. To this end, the idler pulley 336 is rotatably supported on one end of the toggle formed by links 338 and 340, and the other end of the toggle mechanism is held by bolt 342 as is best shown in the view of Figure 13, the bolt 342 depending from the support plate 34.

The toggle linkage formed by the links 340 and 338 is urged to a retracted position by the spring 344, thereby holding the idler pulley 336 out of engagement with the belt 152. As is best shown in Figure 7, the idler pulley 336 is also held in position by the L-shaped arm 346 which is pivotally supported from the bolt 348 depending from the support plate 34. This L-shaped plate limits the movements of the idler pulley 336 to engaging and disengaging movements relative to the belt 152 as the toggle defined by links 340 and 338 is actuated.

The pin 350 which holds toggle links 338 and 340 is supported on the extending tongue 352 of the solenoid mechanism indicated generally at 124. At its remote end this tongue is received within the winding 354 and defines a magnetic plunger 356. The winding 354 is mounted within the magnetic core 358 which has a rectangular window within which this solenoid is mounted and which has a central tongue portion 360 about which the winding extends. Thus, when the winding 354 is energized, the plunger 356 is drawn into the winding 354 to a point in proximity to the end of the tongue 360 as indicated in Figure 7, thereby pulling the tongue 352 to extend the toggle links 338 and 340 against the bias of spring 344 and shift the idler wheel 336 to engagement with the belt 152, thereby urging that belt against the pulley 300 and driving the suds pump 224.

The bowl 320 coacts with the diaphragm or baffle 324 to define a priming chamber into which the pipe 326 extends. This chamber fills with liquid when the tub T is drained by operation of pump 128 (Figure 3). Subsequently, when pump 224 is actuated, the fluid retained in this chamber acts as priming fluid and thereby causes pump 224 to pump immediately, and the possibility of failure for lack of priming fluid is avoided.

As is shown best in the cross-sectional view of Figure 14, the support bolt 348 is attached to and depends from the support plate 34. At its bottom end this bolt defines a shoulder against which the upper support plate 359 of the solenoid 124 is bottomed. The lower support plate 361 is held on bolt 348 by the spring clip 363. The channel shaped arm 346 is received on the bolt 348 intermediate the support plates 359 and 361 for pivotal movements about the axis thereof.

Similarly, the support bolt 342 (Figure 13) is attached to and depends from support plate 34 and defines a shoulder at its bottom end against which the channel shaped portion of link 340 bottoms. The link 340 is held on this bolt by spring clip 341. Bolt 342 is also provided with a peripheral groove 345 to receive the hooked end portion of spring 344.

While I have shown a particular embodiment of my invention, it will, of course, be understood that I do not wish to be limited thereto since many modifications, both in the elements disclosed and their cooperative structure, may be made without departing from the spirit and scope thereof. I, of course, contemplate by the appended claims to cover all such modifications as fall within the true spirit and scope of my invention.

I claim as my invention:

1. In a drive and control mechanism for an automatic laundering machine having a tub, a clothes containing basket journaled therein, an agitator within said basket and journaled for oscillatable movement with respect thereto, an oscillating drive mechanism selectively connectable with said agitator to oscillatably drive said agitator including a drive shaft for said drive mechanism eccentric of the axis of rotation of said basket and having a pulley thereon, another pulley coaxial with the axis of rotation of said basket, a shaft having driving engagement with said basket and having said pulley freely mounted thereon and selectively connectable with said shaft to rotatably drive said basket, two spaced pumps, one being connected with said tub to withdraw fluid therefrom and the other being connected to return fluid to said tub, each of said pumps having a drive pulley thereon, a motor and a single drive connection from said motor to said oscillating drive mechanism for said agitator, said basket and said pumps comprising a belt driven by said motor and having driving connection with said first two pulleys at spaced apart points, a separate run of said belt traveling in alignment with and adjacent each of said pump pulleys, but normally being free from said pulleys, a movable idler pulley associated with each of said pump pulleys on the opposite side of the belt from said pump pulleys, a separate pivotally movable arm supporting each of said idler pulleys, toggle links connected with said pulleys, and a separate rectilinearly movable member operatively connected with each toggle link to independently move said idler pulleys to take up tension on the associated run of the belt and selectively engage the belt with an associated pump drive pulley, to drive the associated pump.

2. In a drive and control mechanism for an automatic laundering machine having a tub, a clothes containing basket journaled therein, an agitator within said basket and journaled for oscillatable movement with respect thereto, an oscillating drive mechanism selectively connectable with said agitator to oscillatably drive said agitator including a drive shaft for said drive

mechanism eccentric of the axis of rotation of said basket and having a pulley thereon, another pulley coaxial with the axis of rotation of said basket, a shaft having driving engagement with said basket and having said pulley freely mounted thereon and selectively connectable with said shaft to rotatably drive said basket, two spaced pumps, one being connected with said tub to withdraw fluid therefrom and the other being connected to return fluid to said tub, each of said pumps having a drive pulley thereon, a motor and a single drive connection from said motor to said oscillating drive mechanism for said agitator, said basket and said pumps comprising a belt driven by said motor and having driving connection with said first two pulleys at spaced apart points, a separate run of said belt traveling in alignment with and adjacent each of said pump pulleys, but normally being free from said pulleys, an idler pulley associated with each of said pump pulleys on the opposite side of the belt from said pump pulleys, separate pivoted arms supporting said idler pulleys and toggle linkage means operatively connected with said pulleys and selectively operable to move said
